CLAIM

The ornamental design for a combined light and ball game housing, substantially as shown and described.

DESCRIPTION

FIG. 1 is a left side elevational view of the combined light and ball game housing, the right side elevation being the same;

FIG. 2 is a frontal elevational view of the combined light and ball game housing;

FIG. 3 is a rear elevational view of the combined light and ball game housing; and

FIG. 4 is a top plan view of the combined light and ball game housing.

FIG. 1.

FIG. 4.
